Inventor,
Geo. C. Taft

United States Patent Office.

GEORGE C. TAFT, OF WORCESTER, MASSACHUSETTS.

Letters Patent No. 97,988, dated December 14, 1869.

IMPROVEMENT IN WRENCHES.

The Schedule referred to in these Letters Patent and making part of the same.

To all whom it may concern:

Be it known that I, GEORGE C. TAFT, of the city and county of Worcester, and Commonwealth of Massachusetts, have invented certain new and useful Improvements in Wrenches; and I do hereby declare that the following is a full, clear, and exact description of the same, reference being had to the accompanying drawings, forming a part of this specification, in which—

Figure 1 represents a side view of my improved wrench;

Figure 2 represents a back view of the same; and

Figure 3 represents a section through the screen on line A B, fig. 1.

To enable those skilled in the art to which my invention belongs, to make and use the same, I will proceed to describe it more in detail.

The nature of my invention relates to that class of wrenches known as **S**, or forked wrenches; and

It consists in the peculiar manner of arranging and combining the rosette and screw with the two parts which form the bar of the wrench, as will be hereafter explained.

By referring to the drawings, it will be seen that the bar of my improved wrench is made in two parts, A and B.

These parts are flattened on their inner sides, and are held securely together by flanges and grooves at their ends, while at their central part they are curved outward in the form of half cylinders *a* and *b*, which extend diagonally across the bars, while in the opening between said half cylinders, are arranged the screw *C* and rosette *D*, by means of which the jaws of the wrench are operated.

The half cylinder *b*, on the lower part B, of the bar, has a head, *c*, cast on one of its ends, in which is firmly secured one end of the screw *C*, while in the centre of the half cylinder *a* is formed an opening, in which fits the rosette *D*.

At each side of the rosette *D*, and formed with the half cylinder *a*, are rings or flanges *e*, that extend around beneath the screen *C*, as shown in fig. 3 of the drawings.

The rosette *D* is provided with a screw-thread, corresponding to that upon the screw *C*, so that as the rosette is turned, the upper half of the bar is moved to open or close the jaws of the wrench.

It will be seen that by constructing the wrench as above described, the screw *C* is protected by the semi-cylindrical parts *a* and *b*, so that the thread is not liable to become injured or to get clogged with dirt.

The rosette and screw being incased in this manner, makes the wrench very compact in form, and also at the same time very strong and durable, and not liable to get out of order.

Having described my improved wrench,

What I claim therein as new, and of my invention, and desire to secure by Letters Patent, is—

1. The combination and relative arrangement, with the parts A and B, of the screw *C* and rosette *D*, substantially as and for the purposes set forth.

2. The combination of the semi-cylindrical parts *a* and *b*, of the divided wrench A B, with the flanges or rings *e*, substantially as and for the purposes set forth.

GEO. C. TAFT.
